UNITED STATES PATENT OFFICE.

LANDON S. SHIELDS, OF MARION, OHIO.

SLIDE-TROMBONE.

987,922.

Specification of Letters Patent. Patented Mar. 28, 1911.

Application filed May 17, 1910. Serial No. 561,862.

To all whom it may concern:

Be it known that I, LANDON S. SHIELDS, citizen of the United States, residing at Marion, in the county of Marion and State 5 of Ohio, have invented certain new and useful Improvements in Slide-Trombones, of which the following is a specification.

This invention comprehends certain new and useful improvements in brass wind instruments and relates particularly to slide 10 trombones.

The invention has for its primary object a slide trombone, the parts of which are so constructed and arranged that a free air 15 passage is provided from one end of the instrument to the other, all shoulders and off-sets being avoided.

With this and other objects in view as will 20 more fully appear as the description proceeds, the invention consists in certain constructions, arrangements and combinations of the parts that I shall hereinafter fully describe and claim.

For a full understanding of the invention, 25 reference is to be had to the following description and accompanying drawings in which: the figure is a longitudinal sectional view of the invention.

Referring to the drawing, the numerals 1 30 and 2 designate the relatively stationary tube sections of the instrument connected together near one end by a transversely extending tube section 3 and provided with the usual stationary cups 4. The slide of the 35 trombone embodies a tube section 5 connected at one end to the curved tube 6 and the latter in turn being connected to or forming part of the tube section 7 which extends parallel to the tube section 5 and 40 which is arranged to telescope within the tube section 2. At the juncture of the tube sections 6 and 7, the same are provided with a cup 8 on the flange or rim of which a sleeve or tube 9 is secured or formed, the 45 sleeve 9 surrounding and spaced from the tube section 7, preferably terminating short of such section, the section 2 of the relatively stationary portion of the trombone working between the concentric tube sections 7 and 9 as clearly illustrated in the 50 drawing. At one limit of the movement of the slide, the tube section 2 will abut against the bottom of the cup 8 and the relatively free end of the section 9 will abut against 55 the bottom of the adjacent cup 4. It is to be particularly noted that the tube sections have

a straight uniform bore, and that each of them is different in caliber from the others, except the sections 5, 6 and 7 which are of the same caliber. By this, means, it is clear, 60 that a free air passage is produced.

In the present instance, the bell of the instrument is not shown or described as it does not form any part of the present invention, being tapered in the usual manner. 65

One end of the tube section 1 is exteriorly enlarged, as indicated at 1^a, this enlarged portion extending to one end of the section and terminating short of the other end in an annular shoulder 1^b, and likewise the section 7 is formed with an exterior enlargement 7^a terminating in an annular shoulder 7^b. By this means oil bearings are produced opening in either direction and as they hold the 75 slideable tubes in line with the stationary tubes, an easy running slide is produced.

From the foregoing description in connection with the accompanying drawings, it will be seen that I have provided a slide 80 trombone so constructed and arranged that each time the air passes from one section of the instrument to another, it passes into a slightly larger air passage, the double casing formed by the sections 7 and 9 serving to support the brace and handle bar 10 as well 85 as to protect the inner parts from the accumulations of dust, while the inner tube 7 being the same caliber as the section 5, it conducts the air around through the slide without encountering any off-sets or shoul- 90 ders.

Having thus described the invention, what is claimed as new is:

1. A slide trombone, embodying relatively 95 stationary parallel tube sections 1 and 2, the latter being of larger caliber than the former, parallel slide sections 5 and 7 of equal caliber one with the other connected at one end by a curved section of corresponding caliber, the section 5 telescoping outside 100 of the section 1 and the section 7 telescoping within the section 2, and a tube section 9 surrounding and concentric to and spaced from the section 7 and connected thereto at one end, the said tube 9 sliding upon the outside 105 of the tube section 2.

2. A slide trombone, embodying relatively 110 stationary parallel tube sections 1 and 2, the latter being of larger caliber than the former, parallel slide sections 5 and 7 of equal caliber one with the other connected at one end by a curved section of corresponding

caliber, the section 5 telescoping outside of the section 1 and the section 7 telescoping within the section 2, and a tube section 9 surrounding and concentric to and spaced 5 from the section 7 and connected thereto at one end, the said tube 9 sliding upon the outside of the tube section 2, the sections 1 and 7 being provided at one end with exterior enlargements, the enlargements of the sec-

tion 1 snugly fitting within the section 5 10 and the enlargement of the section 7 snugly fitting within the section 2.

In testimony whereof I affix my signature in presence of two witnesses.

LANDON S. SHIELDS. [L. S.]
